(57) **CLAIM**

The ornamental design for an eye template, as shown and described.

DESCRIPTION

FIG. 1 is a front elevational view of the eye template showing my new design; the broken lines shown for illustrative purposes only and forms no part of my claimed design; and,

FIG. 2 is a front, elevational view; the rear elevational view is a mirror image thereof.

The side views are of no appreciable thickness.

1 Claim, 2 Drawing Sheets
